UNITED STATES PATENT OFFICE.

GEORGE W. BEADLE, OF BAYONNE, NEW JERSEY, ASSIGNOR TO SINGLE SERVICE PACKAGE CORPORATION OF AMERICA, OF NEW YORK, N. Y.

ROLLER SPINNING-DISK FOR CRIMPING-MACHINES.

1,038,715.

Specification of Letters Patent. Patented Sept. 17, 1912.

Application filed September 30, 1910. Serial No. 584,756.

To all whom it may concern:

Be it known that I, GEORGE W. BEADLE, a citizen of the United States, residing at Bayonne, in the county of Hudson and State of New Jersey, have invented certain new and useful Improvements in Roller Spinning-Disks for Crimping-Machines; and I do hereby declare the following to be a full, clear, and exact description of the invention, such as will enable others skilled in the art to which it appertains to make and use the same.

This invention relates to spinning disks for crimping in the ends of cartons such as is disclosed in my prior application No. 564,602, filed June 2nd, 1910, and entitled "Crimping machines for cartons," and has for its object the improvement of the construction of the prior disks, all as will appear more fully below.

To these ends the invention consists in the novel combinations of parts and details of construction more fully hereinafter described and particularly pointed out in the claims.

Referring to the accompanying drawings forming a part of this specification in which like numerals refer to like parts in all the views, Figure 1 is a plan view of a roller spinning disk made in accordance with my invention; Fig. 2 is a sectional view of the invention taken on the line 2—2 of Fig. 1, and Fig. 3 is a plan view of the roller carrying disk alone.

As fully disclosed in the application above, the spinning disks in machines like those made the subject of said application, have a motion longitudinally of the axis of the carton whose edge is to be crimped, and they then have a rotary motion, during which the spinning operation is accomplished. It is found in practice that unless the material of the carton is first broken down or forced in at intervals around the circumference of the vessel, that the spinning operation is not so satisfactory as could be desired.

In accordance with this invention the spinning disk 1 is provided with a plurality of radially disposed rollers 2 mounted on brackets 3, and having a plurality of grooves 4, one inside the other, as shown. Through an opening 5 in the disk 1, passes a hub 6 of another disk 7, provided with radial slots 8 to accommodate the rollers 2,

as shown. The outer surface of the disk 7 is also preferably provided with concentric grooves 9 which register with the grooves 4 in the rollers 2 as will be readily understood. A spring 10 surrounds the hub 6 and is confined on said hub between the disk 1 and a plate 11 attached to said hub 6, so that when pressure is brought upon the grooves 4 of the rollers, the said disk 1 will cause the spring to be compressed and the rollers will be forced down to the surface of the disk 7 so that the grooves 9 will contact with the edge of the carton and force the same inwardly during the spinning operation. The tension of the spring is so adjusted that the rollers normally stand slightly above the disk 7; and therefore when the said disks 1 and 7 are given a movement longitudinally of the axis of the carton prior to the spinning operation, the said rollers will bite into, break down or upset the material of the carton, at intervals around its circumference, whereupon pressure thus produced upon the spring 10 will cause the said rollers to recede through the disk 7 and will bring the spinning grooves 9 into intimate contact with the broken down edge of the carton. When the parts are in this position a rotary motion is imparted to the disks 1 and 7 and the edge of the carton is neatly and smoothly spun into the desired finished condition.

What I claim is:

1. A spinning disk for carton crimping machines provided with a spinning groove adapted to crimp the edge of a carton to the desired shape; means comprising a roller adapted to break down the material of said edge prior to the crimping operation; and means for moving said disk and groove relatively to said roller, substantially as described.

2. In a carton crimping machine, the combination of a spinning disk provided with a crimping groove and a plurality of radial slots; a plurality of grooved rollers located in said slots; and means for moving said disk, groove and slots relatively to said rollers, substantially as described.

3. In a carton crimping machine, the combination of a spinning disk provided with a crimping groove and a plurality of radial slots, a plurality of grooved rollers located in said slots, means carrying said rollers; and resilient means adapted to move said

carrying means and rollers relatively to said spinning disk, substantially as described.

4. In a carton crimping machine, the combination of a spinning disk provided with a hub, a crimping groove and a plurality of radially disposed slots; a second disk mounted on said hub and provided with a plurality of rollers adapted to move in said slots, and a spring on said hub adapted to

control the movements of said rollers, substantially as described. 10

In testimony whereof, I affix my signature, in presence of two witnesses.

GEORGE W. BEADLE.
